UNITED STATES PATENT OFFICE.

GEORGE W. LANCASTER, OF PETERSBURG, VIRGINIA.

RAILWAY-CROSSING.

SPECIFICATION forming part of Letters Patent No. 777,424, dated December 13, 1904.

Application filed July 29, 1904. Serial No. 218,705. (No model.)

To all whom it may concern:

Be it known that I, GEORGE W. LANCASTER, a citizen of the United States, residing at Petersburg, in the county of Dinwiddie and State 5 of Virginia, have invented new and useful Improvements in Railway-Crossings, of which the following is a specification.

This invention relates to railway-crossings.

The principal object of the invention is to 10 prevent accidents which frequently occur at railway-crossings by a train on one track colliding with a train upon an intersecting track.

The invention aims, further, to simplify and 15 improve the forms of railway-crossings heretofore used to prevent accidents.

With the foregoing and other minor objects 20 in view, which will appear as the description proceeds, the invention resides in a plurality of pairs of intersecting railroad-tracks, one 25 track of each pair having parallel therewith a supplemental rail adapted to be actuated by the flange of a car-wheel, automatic means for holding each supplemental rail against the adjacent track, and means operated by each supplemental rail for opening a derail-switch upon the other pair of tracks and simultaneously actuating a signal.

The invention also resides in the particular 30 combination and arrangement of parts and in the precise details of construction hereinafter described and claimed as a practical embodiment of the invention.

In the accompanying drawings, forming 35 part of this specification, Figure 1 is a plan view of a railroad-crossing embodying the features of the invention. Fig. 2 is a section on the line 2 2 of Fig. 1. Fig. 3 is a similar section on the line 3 3 of Fig. 1. Fig. 4 is a section on the line 4 4 of Fig. 1.

Like reference-numerals indicate 40 corresponding parts in the different figures of the drawings.

The reference-numerals 1 2 indicate a pair 45 of railroad-tracks which are intersected by a similar pair of tracks 3 4. The tracks 1 2 and 3 4 are mounted upon sleepers 5 in any suitable manner, as shown. Extending parallel with the inner side of each pair of tracks 1 and 4 is a pair of movable supplemental rails

6, the two supplemental rails 6 of each pair 50 of tracks being disposed on opposite sides of the crossing. Each of the supplemental rails 6 is formed with inwardly-bent ends 7. The supplemental rails 6 are adapted to be forced away from the adjacent rails 1 or 4 by the 55 flange of a car-wheel, and the movement of each supplemental rail serves through suitable mechanism, hereinafter to be described, to actuate a derail-switch located upon the opposite pair of tracks. Disposed opposite each 60 of the movable supplemental rails 6 is a stationary supplemental rail 8, having inwardly-curved ends. Connected in any suitable manner with each of the stationary supplemental rails 8 is a set or plurality of casings 10, said 65 casings being supported, preferably, upon the railroad-ties. Located in each of the casings 10 is a coil-spring 11, as shown in Fig. 3, bearing against the piston-head 12 of a rod 13, connected with the adjacent movable supplemental rail 6. The set or plurality of coil-springs 11 serves as automatic means for holding the movable supplemental rails against the adjacent track 1 or 4, as the case may be. Attached to each of the movable supplemental 70 rails 6 is a set or plurality of rods 14, which are connected with a set or plurality of bell-crank levers 15, attached in turn to a connecting-rod 16. Each of the connecting-rods 16 is connected, by means of a bell-crank lever 17, with an actuating-rod 18. Each of the actuating-rods 18 at each of its ends is connected with a bell-crank lever 19, which serves to operate a rod 20, connected with a derail-switch 21. Each of the rods 20 is also 85 connected with a shifting lever 22, the free end of which slides upon a suitable trackway 23. Each of the derail-switches 21 is connected, by means of a rod 24, with a bell-crank lever 25, connected in turn, by means of a rod 90 26, with a bell-crank lever 27, which serves to actuate a signal-arm 28 to notify an approaching train that the derail-switch is open. Constructed as above described the operation of the improved switch is as follows: If 95 a train be approaching the crossing on the pair of tracks 1 2, the flange of the car-wheel will force the movable supplemental rail 6

away from the adjacent rail 1, thus actuating the connecting - rod 16, which in turn will actuate the rod 18, and thus open the derail-switches upon the pair of tracks 3 4, whereby 5 a train approaching the crossing 5 or said tracks 3 4 will be derailed before it will have an opportunity to collide with the train upon the tracks 1 2. The signal-arm 28 will be drawn into position to indicate "danger" at 10 the moment the derail-switch is open and will thus serve to notify the engineer of an approaching train that danger is ahead.

In its particular combination and arrangement of parts and in its precise details of construction the crossing of this invention constitutes an improvement over prior crossings of a similar character.

Having thus described the invention, what is claimed is—

- 20 1. The combination with intersecting pairs of railway-tracks, of a pair of supplemental rails parallel with one of the tracks of each pair on opposite sides of the intersecting point, automatic means for holding said supplemental rails against the adjacent tracks, a pair of derail - switches upon each pair of tracks, and means operated by the movement of the supplemental rails on one pair of tracks for opening the derail-switches upon the other 25 pair of tracks.
2. The combination with intersecting pairs of railway-tracks, a pair of movable supplemental rails parallel with the inner side of one of the tracks of each pair on opposite sides 35 of the intersecting point, a stationary supplemental rail opposite each of the movable supplemental rails, a plurality of coil - springs connected with each of the movable supplemental rails and with the opposite stationary rail, a plurality of derail-switches upon each 40 pair of tracks, and means operated by one of the supplemental rails on one pair of tracks

for opening the derail-switches upon the other pair of tracks.

3. The combination with intersecting pairs 45 of railway-tracks, a pair of movable supplemental rails parallel with the inner side of one of the tracks of each pair on opposite sides of the intersecting point, a stationary supplemental rail disposed opposite each of the movable supplemental rails, the ends of the stationary and movable supplemental rails being curved inwardly, a plurality of coil-springs connected with each of the stationary supplemental rails and with the opposite movable supplemental rail, a plurality of derail-switches upon each pair of tracks, and means operated by the movement of a movable supplemental rail on one pair of tracks for opening the derail-switches upon the other pair of 50 tracks.

4. The combination with intersecting pairs of railway-tracks, of a pair of movable supplemental rails parallel with the inner side of one of the tracks on each pair on opposite 65 sides of the intersecting point, a stationary supplemental rail disposed opposite each of the movable supplemental rails, a plurality of coil-springs connected with each of the movable supplemental rails and with the opposite 70 stationary supplemental rail, a set or plurality of bell-crank levers operated by each movable supplemental rail, a connecting-rod operated by each set of bell-crank levers, an actuating-rod operated by each connecting-rod, 75 a plurality of derail-switches operated by the actuating-rods, and a signal operated by each of the derail-switches.

In testimony whereof I affix my signature in presence of two witnesses.

GEORGE W. LANCASTER.
